ADVERTISING PENCIL, PEN, OR THE LIKE

Joseph V. Wuestman, Union, N. J.

Application June 6, 1940, Serial No. 339,055

7 Claims. (Cl. 40—19)

This invention relates to a novel pencil, pen or the like having incorporated advertising means.

The invention has for an object to provide, in combination with a pencil, pen or the like, novel means for displaying advertising matter.

The invention has for a further object to provide, in a pencil, pen or the like, incorporated advertising means including means arranged to permit movement of an advertisement bearing element, whereby the eye is quickly attracted to the advertising matter and the observer's attention thus invited thereto.

Other objects of this invention, not at this time more particularly enumerated, will be understood from the following detailed description of the same.

Illustrative embodiments of the invention are shown in the accompanying drawing, in which:

Fig. 1 is an elevational view of a pencil provided with the novel means for displaying advertising matter according to this invention, a movable advertisement bearing element of said display means being shown in one position thereof; Fig. 2 is a fragmentary view similar to that of Fig. 1, but showing the movable advertisement bearing element in another position thereof; Fig. 3 is a longitudinal sectional view, taken on line 3—3 in Fig. 1; and Fig. 4 is a transverse sectional view taken on line 4—4 in Fig. 3, but drawn on an enlarged scale.

Figs. 5 to 7 are respectively transverse sectional views similar to that of Fig. 4, but showing various modifications of the advertising display means.

Similar characters of reference are employed in the above described views, to indicate corresponding parts.

In the embodiment of this invention shown in Figs. 1 to 4 inclusive, the invention is illustrated as applied to the barrel 10 of a mechanical pencil, although it will be obvious that the same may be applied to various forms of pencils, pen or pencil cases, pens or the like.

To the upper end of the pencil barrel 10 is affixed a transparent chambered section within which is mounted advertising display means according to this invention. This chambered section comprises a tubular and preferably cylindrical body member 11 made of any suitable transparent material, such as glass or a transparent plastic composition, preferably the latter. Said body member 11 is closed and sealed at its lower end portion by a lower end plug 12, which is provided with an external, axially extending

coupling element 13 of reduced diameter, the same being adapted to engage and be secured in the upper end portion of the pencil barrel 10. Preferably said coupling element 13 is provided with external screw-threads 14 to screw into said upper end of the pencil barrel. In like manner, said body member 11 is closed and sealed at its upper end portion by an upper end plug 15. If desired, said upper end plug 15 is also provided with an external axially extending coupling element 16 of reduced diameter, the same being adapted to engage and be secured in an ornamental end-piece 17 which may be provided to furnish a pleasing finish to the combined structure.

Extending axially through the interior of said transparent body member 11 is a guide bar 18, which is preferably also made of transparent material corresponding to that of said body member 11. The respective end plugs 12 and 15 are provided in their inner portions with centrally disposed sockets 19 to receive the respective ends of said guide bar 18, thus rigidly supporting the latter in axial extension therebetween and centrally through the interior of said body member 11. Said guide bar 18, in one embodiment thereof shown in Figs. 3 and 4, is cylindrical in form, and, when of such shape, is provided with a longitudinally disposed spline or guide channel 20 extending from end to end thereof.

Slidably mounted around said guide bar 18 is a movable carrier sleeve 21 of a length substantially less than that of the chambered interior of said body member 11. This carrier sleeve 21 is preferably in the form of a metallic tube which is disposed between the guide bar 18 and the sides of the body member 11, and thus concentric thereto. To prevent rotation of said carrier sleeve 21 the same is provided with feather or key means 22 adapted to enter and ride in said spline or guide channel 20 of the guide bar 18. Suitably applied to the external surface of said carrier sleeve 21 is an advertising display 23 of desired character. In like manner, suitably applied to the external surface of said guide bar 18 is an additional stationary advertising display 24, the subject matter of which is preferably divided into a plurality of independent subject sections, as, for example, a lower subject section A (see Fig. 1) and an upper subject section B (see Fig. 2). These subject sections may comprise either unrelated advertising matter, or advertising matter which is suitably correlated to that carried by the movable carrier sleeve 21.

The carrier sleeve 21 has a loose, easily sliding fitted relation to said guide bar 18 so as to move freely along the same, and over the advertising display carried by said guide bar 18. The interior of the chamber of the transparent body member is filled with a transparent liquid 25, such, for example, as a light transparent oil. This liquid content acts to control gravitation of the movable carrier sleeve 21 in such manner as to offer some resistance thereto, whereby the gravitational movement of said carrier sleeve is sufficiently retarded to assure a comparatively slow or gradual movement of the carrier sleeve from one end to the other of the chambered body member. Since the transparent liquid 25 fills the interior of the chambered body member, it cooperates with the transparent walls of the latter to produce sufficient magnification of the advertising displays, and especially those mounted on the guide bar 18, to effect the illusion that said displays are viewed substantially at the outer surface of the walls of said body member 11.

When the pencil is held point down, as shown in Fig. 1, and the movable carrier sleeve 21 occupies its uppermost position in the chamber of the body member 11, the upper subject B of the stationary advertising display 24 is covered and concealed by the surrounding carrier sleeve 21, and, in such case, the advertising display 23 on the sleeve may be read in connection with the lower subject A of the stationary advertising display 24. Since, however, the carrier sleeve 21 is free to gravitate, when the pencil is held point down, as above mentioned, said carrier sleeve will, by gravity, be caused to move slowly downward through the resisting liquid 25, thus gradually shutting from view said lower subject A, while at the same time disclosing to view the upper subject B of the stationary advertising display, whereby, when the carrier sleeve comes to rest at the lower end of the chambered body member 11, said latter display may thereupon be read in conjunction with the display carried by said carrier sleeve. By inverting the pencil, the reverse of these operations takes place. As will be understood the described movements of the carrier sleeve 21 will serve to quickly attract the eye to the advertising matter so that observer's attention is invited thereto.

While in the above described embodiment of the invention, the carrier sleeve and its guide bar are of cylindrical form, it will be obvious that the same may be of other cross-sectional shapes if desired. For example, as shown in Fig. 5, the guide bar 18' may be of relatively thin flat formation, the opposite faces of which are adapted to bear different advertising displays 26 and 27, while the cooperating carrier sleeve 21' is of conforming cross-section shape, adapted to also bear on its opposite faces different advertising displays 28 and 29. To further illustrate similar variation, the guide-bar 18'' may be of triangular cross-sectional shape (as shown in Fig. 6), or of any other polygonal cross-sectional shape, the several faces of which may respectively bear individual advertising displays 30, 31 and 32, while the carrier sleeve 21'' is of conforming cross-sectional shape, and adapted to likewise bear on its several external faces separate advertising displays 33, 34 and 35. In the modified structures above referred to, since the guide bars and cooperating carrier sleeves are of substantially polygonal cross-sectional shape, the latter are incapable of turning on the former,

and consequently the spline or guide channel 28 and cooperating feather or key means 22 of the first described construction may be omitted.

In a simple form of the device, wherein movable and stationary advertising displays, either independent or correlated, are not desired, then the guide bar structure may be omitted, and merely the movable carrier sleeve 21 with its advertising display 23 alone employed, as shown in Fig. 7.

It will be apparent from the above description that the instant invention provides an interesting and effective means, in combination with a pencil or like device, for the display of desired advertising matter, wherein, due to the movable carrier element thereof, an effect means is afforded for quickly attracting the eye and attention of the observer to the advertising matter.

Various other changes could be made in the structures herein shown and described without departing from the scope of this invention as defined in the following claims. It is therefore intended that all matter contained in the above description or shown in the accompanying drawing shall be interpreted as illustrative and not in a limiting sense.

I claim:

1. In a device of the kind described, a transparent chambered section having closed ends, a transparent liquid filling said section interior, a fixed guide bar extending axially through said section interior from end to end thereof, a carrier means slidable on said guide bar and adapted to move by gravity from end to end of said section interior through the liquid contained therein, said guide bar bearing advertising display adapted to be concealed in part and exposed in part by movements of said carrier means along said guide bar, and said carrier means also bearing advertising display, said advertising displays being visible through said liquid and the transparent walls of said section.

2. In a device of the kind described as defined in claim 1 wherein said carrier means and guide rod are provided with cooperative means to effect a non-rotative splined relation of the former to the latter.

3. In the barrel of a pencil, pen or the like, a chambered section comprising a transparent tubular body member, a closure plug to seal the lower end of said body member and having means to couple the same to said barrel, a second closure plug to seal the upper end of said body member, a transparent liquid filling the interior of said body member, a guide bar having its respective ends anchored to said respective closure plugs and disposed to extend axially through said body member interior, a carrier means slidable on said guide bar adapted to move by gravity from end to end of said body member interior through the liquid contained therein, said guide bar bearing advertising display adapted to be concealed in part and exposed in part by movements of said carrier means along said guide bar, and said carrier means also bearing advertising display, said advertising displays being visible through said liquid and the transparent walls of said body member.

4. The combination defined in claim 3 including cooperative means on said carrier means and guide rod adapted to effect a non-rotative splined relation of the former to the latter.

5. In a device of the kind described, a transparent chambered section having closed ends, a

transparent liquid filling said chambered section, a stationary advertising element and a movable advertising element within said chambered section, said movable advertising element being slidably related to said stationary advertising element and adapted to move by gravity between the ends of said chambered section through the liquid contained therein and relative to said stationary advertising element.

6. In a device of the kind described, a transparent chambered section having closed ends, a transparent liquid filling said chambered section, an advertising element submerged in said liquid but adapted to move under gravity endwise there-through between the ends of said chambered section, and means within said chambered section

5 to guide such endwise movement of said advertising element.

7. In a device of the kind described, a transparent chambered section having closed ends, a transparent liquid filling said section interior, a fixed guide means extending axially of said section interior, a movable advertising means guided by said guide means and adapted to move by gravity between the ends of said section interior through the liquid contained therein, said guide means bearing advertising display, said movable advertising means and said advertising display of said guide means being visible through said liquid and the transparent walls of said section.

10 15 JOSEPH V. WUESTMAN.
